(57) **CLAIM**

The ornamental design for a ice hole fishing illuminating warmer, as shown and described.

DESCRIPTION

FIG. 1 is a left front perspective view of the ice hole fishing illuminating warmer showing my new design;

FIG. 2 is a front perspective view thereof;

FIG. 3 is a top plan view thereof;

FIG. 4 is a rear perspective view thereof;

FIG. 5 is a left side perspective view thereof; and,

FIG. 6 is a bottom plan view thereof.

The invention is symmetrical on the right and left side.

The broken lines shown in the drawings illustrate environmental structure only and forms no part of the claimed design.
